UNITED STATES PATENT OFFICE.

JAMES CRAWFORD, OF BOSTON, MASSACHUSETTS.

CLEAN-OUT FOR DRAIN OR SOIL PIPES.

SPECIFICATION forming part of Letters Patent No. 694,140, dated February 25, 1902.

Application filed June 6, 1901. Serial No. 63,420. (No model.)

To all whom it may concern:

Be it known that I, JAMES CRAWFORD, a citizen of the United States, residing at Boston, in the county of Suffolk and State of Massachusetts, have invented new and useful Improvements in Clean-Outs for Drain or Soil Pipes, of which the following is a specification.

This invention relates to improvements in clean-out for drain or soil pipes, as will hereinafter be more fully shown and described, reference being had to the accompanying drawings, where—

Figure 1 represents a top plan view of the improved clean-out. Fig. 2 represents a central longitudinal section on the line 2 2 shown in Fig. 1. Fig. 3 represents a horizontal section on the line 3 3 shown in Fig. 2. Fig. 4 represents a sectional view similar to Fig. 2, showing the metal cap and screw-threaded brass ring removed from the body portion of the device. Fig. 5 represents a side elevation of the internally-screw-threaded brass ring to which the brass cap is detachably connected. Fig. 6 represents a cross-section of said screw-threaded brass ring, taken on the line 6 6 shown in Fig. 5; and Fig. 7 represents a cross-section on the line 7 7 shown in Fig. 4.

Similar letters refer to similar parts whenever they occur on the different parts of the drawings.

In the drawings, A represents the brass cap or cover, as usual having on its under side an externally-screw-threaded portion A' and having on its upper side a hexagonal or equivalent projection A'', adapted to be turned by means of a suitable wrench, as usual, for securing such cap in place or removing it when so desired.

B is the cast-iron body of the clean-out, the lower end of which is suitably connected to the soil or drain pipe C, as usual.

In devices of this kind the cap A is usually made of brass, and the body B, into which the cap A is screwed, is either made of brass or cast-iron. Making such entire body portion of brass is objectionable on account of the expense incurred. Making such body portion of cast-iron is objectionable on account of its interior upper screw-threaded portion being liable to oxidation, disintegration by rust, and thereby adhering to the screw-cap, so as to prevent its ready removal in using the clean-

out, and to obviate such objections I construct my device as follows: To the interior upper portion of the cast-iron body B, I secure a brass ring D, having an internal screw-thread adapted to receive the screw-threaded portion of the brass cap A, as shown in Figs. 2, 3, 5, and 6. The said brass ring D and upper portion of the cast-iron body B are cast together either by first casting said brass ring D and afterward casting the upper portion of the body B around it or by first casting said body B and afterward casting the brass ring D within said body B, as may be most suitable and practical. For the purpose of securing said brass ring D within the interior of the upper portion of the body B, I prefer to make the outer periphery of said brass ring upwardly tapering, as shown at d in Fig. 5, adapted to be received in a correspondingly-shaped interior annular tapering recess b in the upper portion of the body B, as shown in Figs. 2 and 4. On the interior of the upper recessed portion b of the body B, I make a series of inwardly-projecting lugs b' b' b', adapted to enter corresponding peripheral recesses d' d' on the brass ring D, as shown in Figs. 5 and 6. By this arrangement I cause the said brass ring D to be firmly secured within the upper portion of the body B, thus preventing said ring D from turning within the body B when securing or removing the cap A. For the purpose of preventing the said brass ring D from moving downward within the body B, I prefer to make on the interior of the latter an annular shoulder or projection B', upon which the said brass ring D is supported, as shown in Figs. 2 and 4.

E in Fig. 2 is a packing-ring arranged between the under side of the cap A and upper end of the body B, as usual. By this arrangement it will be seen that I secure within the upper end of the body B an annular brass ring or lining, screw-threaded on its interior to receive the screw-threaded brass shank A' of the cap A, by which construction the device is materially improved and the working parts prevented from oxidation and disintegration by rust, &c., as hereinabove described.

In the drawings I have shown the interior portion of the body B provided with projections and the exterior of the brass ring D

provided with corresponding recesses; but I wish to state that if so desired the projections may be made on the exterior of the brass ring and the corresponding recesses made on the interior of the body B without departing from the essence of my invention.

What I wish to secure by Letters Patent and claim is—

The herein-described clean-out, consisting 10 of a screw-threaded removable brass cap A combined with an internally-screw-threaded brass ring having notches or projections on its exterior, interlocked with corresponding projections or recesses on the interior of the

cast-iron body portion B, and an annular projection or shoulder B' on the interior of said body B below the said brass ring D, said shoulder serving as a rest or support for said brass ring substantially as and for the purpose set forth.

In testimony whereof I have hereunto set my hand in presence of two subscribing witnesses.

JAMES CRAWFORD.
